(57) CLAIM

The ornamental design for a horse owner's and farrier's stand, as shown and described.

DESCRIPTION

FIG. 1 is a perspective view of the invented design for a horse owner's and farrier's stand, with a buttress design and a knob and a magnet.

FIG. 2 is a frontal view of the design depicted in FIG. 1.

FIG. 3 is a side view of the design depicted in FIG. 1, taken from the right side.

FIG. 4 is a side view of the design depicted in FIG. 1, taken from the left side.

FIG. 5 is a bottom view of the design depicted in FIG. 1; and,

FIG. 6 is a top view of the design depicted in FIG. 1.
